UNITED STATES PATENT OFFICE.

JAMES H. PREATER, OF BROOKLYN, NEW YORK.

SHIPPING-DRUM.

SPECIFICATION forming part of Letters Patent No. 327,589, dated October 6, 1885.

Application filed May 18, 1885. Serial No. 165,813. (No model.)

To all whom it may concern:

Be it known that I, JAMES H. PREATER, of Brooklyn, in the county of Kings and State of New York, have invented an Improvement 5 in Shipping-Drums, of which the following is a specification.

Drums have heretofore been made for holding various articles—such as teas, coffees, spices, &c.—the said drums being composed of 10 straw-boards or mill-boards rolled up into a cylindrical form and the ends united, there being a wooden head and a wooden bottom. These drums often require to be shipped from the place where they are manufactured to a 15 distant place, where they are filled. The transportation of the empty drums is expensive because of the great bulk or space occupied.

My improvement is especially intended for lessening the bulk of the drums; and it relates 20 to a knockdown drum that may be shipped from the place of manufacture to the place of filling at very little expense.

I roll up the sheet of straw or mill board into a cylindrical form, after having cut it to 25 the proper size and shape, and I connect with one edge of the cylinder strips of sheet metal folded backwardly and joined together for the reception of the edges of the straw or mill board; and I also use a folded strip of 30 sheet metal near the other edge of the board, and a folded sheet-metal junction-piece to unite the backwardly-folded edges of the sheet metal at the inner surface of the cylinder. The drum is provided with hoops at 35 the ends and top and bottom heads, so that the drum can be put together; but for the purposes of shipment the sheets of straw or other boards are laid out one upon the other, ready to be put together at their destination.

40 In the drawings, Figure 1 is a vertical section of the package or drum complete. Fig. 2 is a section, in magnified size at the ends, of the straw or other board forming the cylinder, where such ends are brought together, 45 and Fig. 3 is a similar view with the end parts of the cylinder slightly separated from each other.

In Letters Patent No. 223,949, issued to me January 27, 1880, a jacket is shown for a drum, 50 the edges of the jacket being drawn together

and united by a folded sheet-metal slide upon the outside of the jacket, that is slipped endwise over the edges of the folded metallic strips attached to and inclosing the straw-board. The folded sheet-metal junction-piece 55 is only adapted for holding together the edges of the jacket.

In my present improvement A represents the cylindrical portion of the drum, the same being made of straw or other board of suitable size, and at the edges of the straw or other board, where they come together, folded metallic strips C D D' are attached.

The strip C is provided with hook-shaped bands E, that are passed through incisions 65 made in and parallel with the edges of the straw-board, so that said strip C is held to the straw-board in a very firm manner by bending up and clinching the ends of the hook-shaped bands.

70 The metal strips D D' at the opposite edge of the straw-board are made of U-shaped pieces of sheet metal set together and soldered at n. The strip D' is adapted to receive and be permanently attached to the edge of the 75 straw-board A. For this purpose pieces of sheet metal l are passed through incisions in the straw-board and folded upon themselves toward the edge of the board, so as to clinch the straw-board, and these pieces of 80 metal l are passed within the U-shaped portion D' and united by solder applied at r.

The strip D is folded back at its edge, as seen at s, and there is a folded sheet-metal slide or junction-piece, T, that is slipped endwise over the folded edges of the pieces C and D, so as to unite the edges of the straw or other board and hold the same in a cylindrical 85 form. By withdrawing this junction-piece T the straw or other board A can be laid out 90 flat, or nearly so, for transportation, and said edges are easily united again in the form of a cylinder by rolling or bending up the parts and slipping on the junction-piece T after the exposed edge of the cylinder A is passed into 95 the U-shaped piece of sheet metal D.

The wooden base or bottom R and the top V are circular, with shoulders for the reception of the ends of the cylinder A, and the hoops P and Q are placed around the outside 100

of the cylinder A, at the ends thereof, as seen in Fig. 1, and small nails are employed, as at 2 and 3, to connect the parts together.

I claim as my invention—

- 5 1. The cylinder A, of straw or mill board, in combination with the sheet-metal strip C, attached to one edge of the said straw-board, and having its edge folded over the metal strips D D', that are U-shaped and united together and securely attached to the other edge of the said cylinder, one edge of the strip D being folded back and the folded sheet-metal junction-strip T, substantially as set forth.
- 10 2. The combination, in a drum, of a cylinder of straw-board or similar material, two U-

shaped strips of sheet metal, D D', set back to back and soldered, the strip D' being adapted to receive and be united to one edge of the straw-board, the sheet-metal strip C, and a fastening device for attaching together 20 the strips C and D upon the edges of such straw-board, heads for the package, and hoops around the cylinder at its junction with the heads, substantially as specified.

Signed by me this 15th day of May, A. D. 25
1885.

JAS. H. PREATER.
